COMBINED TRUCK AND CRANE BODY

William M. Shook, New Philadelphia, Ohio, assignor to
The Warner & Swasey Company, Cleveland, Ohio, a
corporation of Ohio

Filed Oct. 14, 1959, Ser. No. 57,928

Term of patent 14 years

(Cl. D14—3)

FIG. 1

FIG. 1 is a perspective view from the front and to one side of a combined truck and crane body, embodying my new design;

FIG. 2 is a perspective view from the front and side opposite that shown in FIG. 1;

FIG. 3 is a perspective view taken from above, the rear, and to one side;

FIG. 4 is a top plan view;

FIG. 5 is a rear elevational view; and

FIG. 6 is a sectional view looking from approximately along line 6-6 of FIG. 4 and showing the rear of the vehicle operator's cab of the body in elevation.

The portions shown in broken lines are for illustrative purposes only.

What I claim is:

The ornamental design for a combined truck and crane body, substantially as shown and described.
